Application February 28, 1955, Serial No. 491,065

2 Claims. (Cl. 100—269)

This invention relates generally to hydraulic presses, and more particularly to hydraulic presses provided with minimum valve pressure accumulator means for effecting a rapid travel of the press ram during the final portion of its pressing stroke.

In hydraulic presses of various types, more particularly in welding presses and in presses for moulding plastic materials, it is necessary to provide for rapid progression of the press ram as soon as there appears a decrease of the inherent resistance of the moulded material as a result of its melting or softening. This action in the past has been obtained in the case of welding presses by the arrangement of a strong spring between the press piston and the press plate and in the case of presses for moulding plastic materials by the provision of a pneumatic accumulator. With such arrangements it may be necessary, in the case of welding presses, to reset the spring for changing its tension as the pressing force is altered, and, in the case of presses for working plastic materials, it may be necessary to re-adjust the control device maintaining the pressure in the pneumatic accumulator.

The object of the present invention is to provide a device which will automatically adapt itself to any change of the pressing force. A further object of the invention is to provide an improved hydraulic press system which will provide for quick completion of the pressure stroke of the ram upon decrease in material resistance by accumulator means arranged in the head of the press cylinder and acting directly upon the press piston.

The invention is diagrammatically illustrated in the accompanying drawing wherein the device is shown partly in section and partly in elevation.

Referring now to the drawing, the vertical press cylinder 1 is divided into an upper accumulator tank 6 and a lower piston chamber by a horizontal intermediate transverse wall. Slidably movable in the piston chamber is a press piston ram 2, the lower extremity of which extends through the bottom wall of the cylinder and is adapted to come into pressing engagement with a work-piece adapted to be positioned on the lower stationary platform. The intermediate transverse wall has an opening therein providing communication between the tank 6 and the portion 5 of the piston chamber above the piston head of the piston ram 2. A minimum valve member 3 vertically movable within the accumulator tank 6 is biased by spring 4 into seating engagement with the opening in the transverse wall to close the same. The ram 2 is controlled by a slide valve 12 slidably movable in housing 7 supplied by oil or other suitable hydraulic fluid from a pump 8. The force of the compression spring 4 of the minimum valve can be adjusted by means of a set screw 16 threadably mounted in the top wall of the cylinder 1. During the pressing stroke of the ram the control lever 11 is pivoted clockwise either manually or automatically to the position shown in the drawing to displace the slide valve 12 to its upper position, thus enabling the hydraulic fluid to enter the space 5 above the ram 2 and after a certain pressure is attained

2

valve 3 will open partially to admit fluid into the accumulator tank 6. As soon as the pressure in chamber portion 5 attains the magnitude of the adjusted moulding pressure, the minimum valve member 3 opens fully, as the upward pressure on the valve exceeds the downward pressure of the compression spring 4. In the space above the level of the hydraulic fluid in the tank 6 there is provided a permanent filling of compressed nitrogen or air which is compressed further by the hydraulic fluid admitted by valve 3 to constitute a small pneumatic accumulator. The introduction of gas into the accumulator tank 6 is controlled by valve 15 in gas supply line 15a. Thus, when the piston is put under pressure by the pressure fluid in chamber portion 5 the rapid completion of the piston pressing stroke will commence as soon as a decrease in the resistance of the moulded material occurs. This action of the piston travel is very quick, since the compressed gas and the fluid in the accumulator exerts pressure from the tank 6 directly through the open minimum valve 3 into the chamber portion 5. Once the pressing operation has been completed, the control lever 11 is rotated counter-clockwise to displace the slide valve 12 to its lower position, and hydraulic fluid enters the lifting space 9 of the press cylinder 1 beneath the piston head of ram 2. The pressure of chamber portion 5 is reduced by communication thereof with the tank 14 through the slide valve housing 7 and discharge pipe 10. During this procedure a part of the hydraulic fluid escapes out of the tank 6 through the opening in the transverse wall 1a. On a decrease of pressure inside the tank 6 below a magnitude corresponding to the force of the compression spring 4, the minimum valve 3 closes automatically thus preventing any further decrease of the pressure inside the tank 6 and any escape of compressed gas contained therein. Therefore a change in the moulding pressure brings about a pressure in the accumulator tank 6 of a magnitude equaling that of the moulding operation pressure.

As soon as the press piston ram 2 reaches its top position, the bottom edge of the piston head opens an overflow conduit containing the return valve 13 and the hydraulic fluid escapes out of the chamber portion 9 through the return valve 13 and further through the housing 7 of the slide valve 12 into the discharge pipe 10 and thence into the tank 14.

After a certain pressure is attained in the chamber 5, the valve 3 admits hydraulic fluid to the tank 6 simultaneously with an increase in pressure in the chamber 5. The admission of fluid to the tank 6 results in compression of the gas in that tank, thereby reducing the rate of increase in downward pressure on the head of the ram 2. This feature is important in welding in that it reduces damage caused by shock.

I claim:

1. A hydraulic press comprising a vertical cylindrical housing having top and bottom walls and a transverse wall dividing said housing into an upper accumulator tank and a lower piston cylinder, said transverse wall having an opening therein providing communication between said piston cylinder and said accumulator tank; a piston ram vertically reciprocable in said piston cylinder, the lower portion of said ram extending through an opening in the bottom wall of said housing and the lower extremity of said piston ram being arranged to come into pressing engagement with a stationary workpiece; means supplying hydraulic fluid under pressure to the piston cylinder, said fluid supplying means including a slide valve for controlling the direction of piston ram travel within said cylinder; means supplying a gaseous fluid under pressure into said accumulator tank; and minimum valve means in said accumulator tank controlling the opening in the transverse wall between the accumulator

tank and the piston cylinder comprising a vertically movable valve member located between the top wall of said cylindrical housing and said transverse wall, spring means in said accumulator tank normally biasing said valve member downwardly into seating engagement with said transverse wall opening to close the same, and an adjusting screw threadably mounted within and extending through an opening in the top wall of said housing with the operating portion thereof extending above said housing top wall for adjusting the tension of said spring to control the minimum pressure of the hydraulic fluid in the piston cylinder above the piston ram which will unseat said valve member.

2. A hydraulic press as defined in claim 1 and further including conduit return means for discharging hydraulic
